Inventor

UNITED STATES PATENT OFFICE.

DANIEL WILLIAMSON, OF SUNBURY, PENNSYLVANIA, ASSIGNOR OF ONE-HALF TO JASPER SLAYMAKER, OF SAME PLACE.

MACHINE FOR CUTTING ICE.

SPECIFICATION forming part of Letters Patent No. 423,652, dated March 18, 1890.

Application filed May 17, 1889. Serial No. 311,133. (No model.)

To all whom it may concern:

Be it known that I, DANIEL WILLIAMSON, a citizen of the United States, residing at Sunbury, in the county of Northumberland and State of Pennsylvania, have invented a new and useful Machine for Cutting Ice, of which the following is a specification.

My invention has relation to machines for cutting ice whereby it is divided into regular blocks preparatory to harvesting of the same; and among the objects in view are to simplify the construction, reduce the cost, and provide a machine adapted to be worked by hand and which will perform a maximum amount of work with a minimum amount of labor.

Other objects and advantages of the invention will hereinafter appear, and the novel features thereof will be particularly pointed out in the claim.

Referring to the drawings, Figure 1 is a side elevation of an ice-cutting machine constructed in accordance with my invention, and Fig. 2 is a plan.

Like numerals of reference indicate like parts in all the figures of the drawings.

In practicing my invention I construct a rectangular frame, and the same consists of two lower parallel bars 1 and two upper parallel bars 2, the terminals of each of the latter forming handles 3, by which the machine may be lifted. The upper and lower bars 1 and 2 are connected by vertical end posts or standards 4 and by transverse tie-bars 5. At about the center of the parallel bars 2 I mount a shaft 6, which is the power-shaft of the machine, and terminates at one side in a squared portion 7 for the reception of a similarly-formed eye provided in the lower end of the operating-crank 8. Upon the shaft 6 are mounted a large gear 9 and a small pinion 10.

At the forward end of the machine, and journaled upon a shaft 11, passing through the bars 2, I mount a fly-wheel 12 and a small gear or pinion 13, the small gear or pinion meshing with the large gear 9 of the shaft 6. At the opposite side of the shaft 6 and upon a shaft 14 is mounted a gear 15 of a size, preferably, the same as the gear 9, and upon this shaft is also mounted a small gear or pinion 16 of a size agreeing with the small pinion 10. The pinion 16 is driven by the shaft 14, which shaft

is in turn driven by the gear 15, meshing with the gear 10 on the shaft 6.

17 represents diagonal vertically-disposed bars, which connect the upper and lower series of bars 1 and 2 near their rear ends and intermediate the uprights 4. In the bars 17 are provided bearings 18, in which is mounted for rotation an axle 19. At each side of the axle 19 and outside of the bars 17 are mounted propelling-wheels 20, the peripheries of which are provided with the usual teeth or spurs. Intermediate the wheels 20 and upon the shaft 19 is mounted a large gear-wheel 21, which meshes with the small pinion 16 of the shaft 6. The two wheels 20 support the rear end of the machine, and the front end thereof is supported by a centrally-located wheel 22, the periphery of which is provided with teeth or spurs, said wheel being mounted upon a shaft 23, journaled in the terminals of the lower bars 1.

In rear of the uprights 4, at the front end of the machine and in the bars 1, is mounted a transverse shaft 24, which carries the ice-cutting wheel 25 of the machine. The wheel 25 consists of a central hub portion 26, radiating spokes 27, which terminate in cutters 28, terminating in rearwardly-curved cutting-edges 28^x. The wheel 25 is rigid upon the shaft upon which it is mounted, and upon the same shaft is mounted a gear 29, the teeth of which mesh with those of the large gear 9, mounted on the shaft 6.

The operation of my invention will at once be apparent, and may be briefly stated as follows: By rotating the crank 8 by hand motion is imparted to the shaft 11 through the medium of the small gear 13, and by said shaft is rotated the fly-wheel 12. As the shaft 6 is rotated by the crank 8 motion is imparted to the gear 15 upon the shaft 14 by the pinion 10. The shaft 14 also rotates the pinion 16, and this pinion meshes with the large gear 21 of the shaft 19. By this peculiar arrangement of gears and transmission of motion from large to small a maximum amount of speed may be gained, and this with inconsiderable hand-labor.

The cutting mechanism, comprising the wheel 25, is operated through the gear 29 meshing with the gear 9, and by reason of their

relative size said cutter-wheel will be revolved in a rapid manner as compared with the remainder of the gears and the speed of the machine.

5 Having described my invention, what I claim is—

In an ice-cutting machine, a system of power-gears in combination with a cutter operated thereby, and consisting of a central hub and
10 a series of radiating spokes or arms the outer

ends of which are bent rearwardly, the outer angles of the arms at their bends being beveled to form cutters, substantially as specified.

In testimony that I claim the foregoing as my own I have hereto affixed my signature in presence of two witnesses.

DANIEL WILLIAMSON.
